Henry D. Williams

UNITED STATES PATENT OFFICE.

HADDEN A. SMITH, OF BROOKLYN, NEW YORK.

MAGAZINE-PENCIL.

1,262,859.

Specification of Letters Patent. Patented Apr. 16, 1918.

Application filed May 12, 1917. Serial No. 168,072.

To all whom it may concern:

Be it known that I, HADDEN A. SMITH, a citizen of the United States, residing at the borough of Brooklyn, in the county of 5 Kings and State of New York, have invented certain new and useful Improvements in Magazine-Pencils, of which the following is a specification, reference being had therein to the accompanying drawings, forming part 10 thereof.

This invention is a magazine pencil designed to hold a number of pencil leads and to feed them successively through the marking end of the pencil as they are worn down 15 in use.

In the accompanying drawings,

Figure 1 is a longitudinal mid-sectional view of the pencil, and

Fig. 2 is a transverse sectional view there- 20 of on the plane 2, 2 of Fig. 1.

A tubular magazine 3 is closed at its rear end by a button 4 and at its front end is contracted in conoidal form and prolonged into a tubular extension 5 of smaller diameter 25 which serves as the lead holder. The lead-holding tube 5 joins the reduced end of the conoid of the lead magazine so that when the pencil is held with the button end up and slightly shaken, one of the leads 6 will be 30 guided into the lead-holding tube 5 and will slide down through this tube until its end projects therefrom. The front end of the holding tube 5 is split as indicated at 7 and the bifurcated halves of the tube are flared 35 away from each other so that when the tube is drawn rearward through the constricted end of the casing 8, the binding action of the casing on the split holder will grip the pencil lead in any desired position. A

40 spring 9 is coiled upon the holding tube 5 and compressed between the front end of the casing and the front end of the pencil reservoir 3, so that it tends always to force the holding tube 5 rearward to grip the pencil lead at the front end of the tube. The casing 8 extends from its constricted end rearwardly in expanding conoidal form until it merges into a tubular form which closely 45 embraces the tubular magazine 3, and the 50 rear end of this casing may be spun down as indicated at 10 to engage the shoulder formed by the overlapping of the magazine 3 on the button 4. The inward flange thus

spun upon the casing will act as a back-stop for the expansion of the spring 9. From this 55 description it will be apparent that when the casing is held in the hand and its button 4 is pressed, the holding tube 5 will be slid forward through the casing aperture so that its split ends may expand and release their 60 grip on the pencil lead which may then be adjusted to any desired position before releasing the button to regrip the lead. The magazine is loaded by holding the pencil casing point upward and pressing the button to expand the end of the holding tube 5, after which the leads may be successively inserted, dropping successively into the magazine.

The invention may be embodied in other 70 constructions, some of which will be obvious to those skilled in the art, and others of which may be inventively devised, all within the spirit and principles and scope of the invention and the following claims.

1. A pencil comprising a tubular lead magazine with a conoidal end, a tubular lead holder projecting from said conoidal end of the magazine and having a split end, a cylindrical casing having a sliding fit over the 80 magazine and having a conoidal end with an aperture sliding over the split end of the holder, and a spring coiled on the holder and compressed between the conoidal end of the magazine and the conoidal end of the casing, and means for sliding the magazine in the casing to compress the spring and release the split end of the lead holder.

2. A pencil comprising a tubular lead magazine with a conoidal end, a tubular lead holder projecting from said conoidal end of the magazine and having a split end, a cylindrical casing having a sliding fit over the magazine and having a conoidal end with an aperture sliding over the split end of the holder, a spring coiled on the holder and compressed between the conoidal end of the magazine and the conoidal end of the holder, and a rearward projection from the magazine which projects from the rear end 95 of the casing.

3. A pencil comprising a tubular lead magazine with a conoidal end, a tubular lead holder projecting from said conoidal end of the magazine and having a split end, a cylindrical casing having a sliding fit over the

magazine and having a conoidal end with an aperture sliding over the split end of the holder, a spring coiled on the holder and compressed between the conoidal end of the magazine and the conoidal end of the casing, a button secured in the rear end of the magazine and projecting from the casing,

and an inward flange formed on the rear end of the casing around said button to engage the rear end of the magazine and act as a stop for the spring.

In testimony whereof I have affixed my signature.

HADDEN A. SMITH.
